Matthew J. Radosevich, 817 1st Ave. NW.,
Chisholm, Minn. 55719

Filed Jan. 17, 1966, Ser. No. 621

Term of patent 3½ years

(Cl. D9—6)

FIGURE 1 is a side elevational view of a snow scraper for roofs showing my new design, a handle to which the same is attached for use being shown in broken lines.

FIGURE 2 is a front elevational view thereof.

FIGURE 3 is a top plan view thereof.

FIGURE 4 is a rear elevational view on line 4—4 of FIGURE 1.

FIGURE 5 is a bottom view thereof.

The dominant features reside in the solid line portion.

I claim:

The ornamental design for a snow scraper for roofs, as shown and described.
